(57) **CLAIM**

The ornamental design for a hard disk drive, as shown and described.

DESCRIPTION

FIG. 1 is a bottom and front perspective view of a hard disk drive showing our new design;

FIG. 2 is a top and rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a partial enlarged view taken from circle 9 in FIG. 1.

The dash-dash broken lines in the drawings depict the portions of the hard disk drive which form no part of the claimed design.

The dot-dash broken lines in the drawings are included for the purpose of referencing the enlargements only, and form no part of the claim.

1 Claim, 9 Drawing Sheets
